UNITED STATES PATENT OFFICE

2,045,067

WOOD BLOCK

Robert G. Bruce, Memphis, Tenn., assignor to
 E. L. Bruce Company, Memphis, Tenn., a corporation of Delaware

Application December 8, 1930, Serial No. 500,963

1 Claim. (Cl. 20—8)

My invention relates to a wood block for use in floors, walls, ceilings and similar places and has particularly in view the production of a fabricated block that can be laid without the use of slip tongues, i. e. tongues that are slipped into position during the laying of the blocks in the floor.

Referring to the drawing for a more complete disclosure of the invention

Fig. 1 is a top view of the finished block with fragmentary sections,

Fig. 2 is a section on the line 2—2 of Fig. 1.

Fig. 3 is a section on the line 3—3 of Fig. 1.

The fabricated block consists preferably of short strips of flooring 2, with the grain running lengthwise of the strips, and having a groove 3 along one longitudinal edge of the strips into which fits the tongue 4 along the opposite edge of the adjacent strips. The underside of the flooring strips is provided with the customary "hollow back" 5 and there is the customary clearance or "relief" 6 between the strips. Before or after the strips have been assembled to form a block, grooves 7 are cut in the ends of the strips. The strips are fitted tongue to groove and are locked together in any suitable manner, such as by means of a metal spline 8, tightly fitting in the groove 9, as fully described and claimed in the patent of C. W. Allen 1,808,623 granted June 2, 1931.

When the fabricated block is thus far assembled, there is an integral tongue 10 running lengthwise of the grain of the block, and a groove 11 also running lengthwise of the grain of the block.

In addition there are two grooves 7 heretofore described and running transversely of the grain of the strips. A block of such construction is disclosed in the patent to Werner Fetz 1,778,068 October 14, 1930, wherein slip tongues are used in the laying of the blocks in a floor.

It has been found advantageous to dispense with slip tongues in the laying of wood block flooring, using instead a wood block that has two integral tongues as disclosed in the patent to Fetz 1,778,069 October 14, 1930.

One of the advantages from a manufacturing standpoint of the block disclosed in Patent No. 1,778,068, having one tongue and three grooves, as compared with the block disclosed in Patent No. 1,778,069, having two integral tongues, is that it is possible to use shorter strips for the former

as compared with the latter, for blocks having the same face dimensions.

In making the same size blocks, i. e. with the same face dimensions, one having two integral tongues at right angles to each other, and the other having a single integral tongue and three grooves, the overall dimensions of the strips in the former will be longer than that of the strips in the latter to the extent of the depth of the tongue, which is normally about $\frac{1}{4}$ of an inch. The saving of material due to the use of shorter slats, where large quantities are used becomes a factor in the cost of production.

By my improved block, I am able to secure some of the advantages of both of the types of blocks disclosed in the Fetz patents.

Into one of the grooves 7, I press a wood spline 12, with a sufficiently tight fit, so that it will remain securely fixed in position without the use of glue, although of course it could be glued in with the same effect. The grain of the spline 12 runs lengthwise of the spline and serves to make the block more rigid. After the spline or tongue 12 is in position, it is remachined, so as to bring it to exact size for freely fitting the groove of the adjacent block. Providing a tongue of this type permits the use of wastewood in manufacturing the spline.

While I have illustrated my invention in connection with two tongue blocks in which the adjacent corners are cut away to permit interfitting of the blocks, the same construction can be used with right and left blocks, as disclosed in the aforesaid patent to Fetz No. 1,778,069.

I claim:

The method of manufacturing a wood block that is made up of a plurality of slats secured together with the grain of the wood running lengthwise of the slats and having two tongues and two grooves at an angle to and adjacent to each other respectively, comprising providing a block with an integral tongue on one edge and along the longitudinal side of one of the slats, securely fastening in the groove of the block that is cut transversely of the grain of the wood, a wooden spline tongue in which the grain of the wood runs lengthwise of the spline and machining the said wooden spline tongue to size after it has been secured in position in said groove.

ROBERT G. BRUCE.
